MAGNETIC HORN

Application filed March 25, 1926. Serial No. 97,386.

This invention relates to horns or sound signals of the type in which a diaphragm is actuated by means of an electro-magnet acting upon an armature attached to the diaphragm. It has been found that the correct operation of such a horn depends largely upon the extent of the air gap between the armature and the magnet, and that for best results it is necessary to adjust this air gap accurately in each horn. The object of the present invention is to provide simple, inexpensive and convenient means for accomplishing such adjustment, and to this end it is proposed to use a spacing member interposed between two of the members of the horn and subject to the application of pressure by means of a bolt or a screw-threaded stud, this spacer being so formed that when subjected to sufficient pressure it may be slightly collapsed or reduced in thickness, so as to permit a change in the normal air gap of the magnetic circuit.

In the accompanying drawings, Fig. 1 is a side elevation, partly in section, of a horn embodying the present invention. Fig. 2 is an enlarged detail view, showing the spacing washer, and adjacent parts, as used in Fig. 1. Fig. 3 is a sectional view on the line 3—3 in Fig. 2; and Fig. 4 is a detail view of a modified form of the invention.

The invention is illustrated as embodied in a horn having a corrugated metal diaphragm 5 which is clamped, at its margin, between a shell or body member 6 and a front plate 7. A horn-proper or projector 8 is attached to the front plate in the usual manner. The armature is shown as having the form of a metal bar 9, while the magnet comprises a central core 10 surrounded by a winding 11. This winding may be energized by an alternating or pulsating current in any convenient manner.

The armature bar 9 is shown as attached to the middle of the diaphragm by means of a bolt 12, this bolt having a wide head 13 which constitutes a part of the magnetic circuit, and a nut 14 is screwed on the other end of the bolt.

The spacer, in which the present invention particularly resides, is shown in Figs. 1 and 2

as interposed between the diaphragm and the armature. It is preferably drawn from sheet metal of suitable thickness, and has a cup-like general form comprising a short cylindrical portion 15 with a peripheral flange 16. The diaphragm is clamped between this flange 16 and a thick washer 18, these parts being drawn tightly together by the action of the nut and the bolt.

In order to permit the spacer to be compressed or collapsed for the purpose set forth, its rear end comprises a convex or dome-like portion 17 which rests against the armature. This form is sufficiently stiff to permit the parts to be clamped tightly together and to be unyielding normally; but if the nut be turned with sufficient force, the portion 17 may be more or less flattened, thus permitting the armature to be drawn nearer to the diaphragm, and this causes the air gap between the magnet core and the bolt to be increased.

The parts of the horn are preferably so designed that when the horn is originally assembled the air gap is in all cases somewhat less than that desired, and the air gap may then be increased to the necessary degree by turning the nut and collapsing the spacer as just described. In order to prevent the parts from being turned out of their proper position when the nut is turned, the bolt is flattened on two sides, as shown, the openings in the diaphragm, the armature and the washer 18 being formed to correspond.

The compressible spacer is not necessarily interposed between the armature and the diaphragm, but it may be used at any other point where it can affect the air gap. For example, as shown in Fig. 4, it may be interposed between the body shell 6 and the magnet. In this case the magnetic core is provided with a threaded and flattened shank 19, and a nut 20 is screwed upon the rear end of this shank. By tightening this nut the spacer may be collapsed so as to permit the magnet to move rearwardly and thus increase the air gap.

It will be apparent that as the convex end of the spacer is flattened, the diameter of its area of engagement with the armature or other part is increased, while its resistance to

further deformation is increased, owing to the increasing abruptness in the bend of the metal. For these reasons the spacer tends automatically to preserve the parallel relation of the parts between which it is interposed, since, if the spacer chances to be collapsed more on one side of the axis than the other, the resistance to further deformation at that side becomes greater than the resistance at the opposite side, and the tendency to unequal deformation thus corrects itself.

5 The spacer need not have the precise form and construction shown and described, the essential point being that it be of such material and such form that it is capable of deformation, but is substantially rigid both before and after such deformation.

10 The invention claimed is:

1. In a magnetic horn, the combination, 15 with horn members comprising a body and a diaphragm, and with electromagnetic actuating members comprising a magnet and an armature, attached respectively to said horn members, of a spacing member interposed 20 between one of said horn members and the actuating member which is attached thereto, said spacing member being in the form of a continuous sheet-metal cup, centrally perforated to receive fastening means, and having 25 a rigid lip and a deformable convex bottom, and screw-threaded fastening means securing the horn member, actuating member and spacing member rigidly together and adapted, upon the application of sufficient force, 30 to subject the spacing member to said abnormal pressure for the purpose of adjustment.

2. In a magnetic horn, a spacer, for the 35 purpose described, in the form of a continuous sheet-metal cup, centrally perforated to receive fastening means, and having a rigid lip and a deformable convex bottom.

40 3. In a magnetic horn, a spacer, for the purpose described, in the form of a sheet-metal cup having a continuous, rigid outwardly-flanged lip and a centrally perforated convex bottom adapted to be flattened 45 under pressure.
